UNITED STATES PATENT OFFICE.

HUGH GELLROY BUCHAN, OF WOODBRIDGE, NEW JERSEY.

BINDER AND SECURING-JOINT THEREFOR, AND FOR OTHER PURPOSES.

1,280,154.

Specification of Letters Patent.

Patented Oct. 1, 1918.

Application filed September 26, 1913. Serial No. 791,964.

To all whom it may concern:

Be it known that I, HUGH GELLROY BUCHAN, of Woodbridge, in the county of Middlesex, State of New Jersey, have invented certain new and useful Improvements in Binders and Securing-Joints Therefor, and for other purposes, of which the following is a specification.

The object of my invention is:—first, to provide a cheap, simple and strong securing-joint for use in mechanically, and without the aid of adhesives, securing-strips or sheets of leather or other flexible fabrics to the edges of metallic or similar strips, or straight-edges, which strips or straight-edges are usually but not necessarily, (when used in loose leaf binders) of substantially segmental form in cross-section; and, second, to provide bindings of all sorts, having a metallic or partially metallic back-piece, (whether such binders are of the form known as loose leaf binders or are a permanent binding), with such mechanical securing or locking joint, by the use of which the side-pieces or binding-boards of the binder may be easily and quickly secured to the back-piece or pieces, in such manner as to be absolutely safe against any but intentional separation therefrom.

My said invention consists, broadly, in a discovery of the fact, and practical applications thereof, that when a flexible fabric is doubled upon itself, and the fold thereof inserted through a narrow slit left in a coil formed upon the edge of a metallic or similar straight-edge, and a rod or other binding key-piece is inserted in the central portion of the fold; and the end of the fabric then drawn around and over the coil, that when properly made, the greater the strain brought upon such fold the greater will be the grip between the straight-edge and fabric at the joint thus formed; and that if the metal is of sufficient strength the joint thus made between the fabric and the coil upon the straight-edge, cannot be broken by strain exerted thereon between the parts, except by fracture of the straight-edge or fabric; and this without the use of any adhesives whatsoever.

In the improved form of bookbinding shown in the drawing hereof, my said invention is shown in one of its many uses to which the said joint may be applied, as forming part of the construction of a particular form of binder adapted to be used

for the binding together and holding of a body of loose leaves, or a pamphlet, (such, for instance, as a telephone directory), which pamphlet or body of leaves while held securely in position in the stiff-back binder of my invention herein shown, may be instantaneously removed, and as instantaneously reinserted therein; but which will at all times be held firmly in place in the binding against any accidental or unintentional removal or displacement thereof.

My said invention is fully shown and described in the following specification of which the accompanying drawing forms a part, wherein similar letters or numerals of reference designate like or equivalent parts, wherever found throughout the several views, and in which:—

Figure 1 is a view from the bottom taken in perspective, partially in section, of a binder, embodying my broad invention in one of the many forms in which I may make the same.

Fig. 2 is an end view from the bottom in cross-section of such binder, taken on the line *a—a* of Fig. 1, showing the pamphlet or bundle of loose leaves in position, and the back strained backward into the open position, to allow of the easy insertion or removal of such pamphlet or bundle of leaves.

Fig. 3 is a view in detail on an enlarged scale, taken on the same sectional line as Fig. 2, of one of the two securing-joints, and adjacent parts shown in such Fig. 2.

Fig. 4 is a front view in detail looking from the right and toward the left of Fig. 1, of one of the three back-springs shown or indicated in Fig. 1, having at the edges thereof the coil forming a portion of my improved fabric securing-joint, as the same appears when removed from such binding; and

Fig. 5 is a top view of a simple straight-edge adapted for use in any device where fabrics are to be secured to metals or other solids, having a fabric securing-coil at its front edge for securing the fabric thereto; a portion of the drawing being broken away to show the manner of securing the securing-rod or binding key-piece in the securing-coil so as to firmly bind the fabric in position.

Referring to the drawing:—

The reference letters A and A', designate the binding or cover-boards of my improved binder, and B the pamphlet or body of loose-

leaves to be bound therein; while C, C', and C'', designate the resilient spring or springs forming a portion of the back of the binder. Such resilient spring may in some cases extend the entire length of the binder, but is usually and preferably divided into a plurality of narrow springs as indicated by C, C' and C'' in Fig. 1. These back-springs are usually of substantially the segmental form in cross-section shown, and are each before tempering provided at the straight edges of the piece of thin sheet-metal out of which they are formed, with an inwardly turned securing coil portion 1, between which and the inner surface of the adjacent side-wall of such spring there is left the narrow securing-slit 2.

In order to firmly secure such metallic resilient back-spring or back-piece to each of the side cover-boards A and A' of the binder, two flexible back securing-strips 3 of leather or other suitable stout flexible fabric of sufficient length to extend longitudinally along the entire back of the binder, are each folded upon itself, and the fold or loop 8 inserted in the securing-coils 2 of the springs C, C', and C'', and after the insertion of a binding key-piece 9 within such fold and coils, as shown in Figs. 1, 2, 3 and 5, the two plies of such folded fabric securing-strip are then drawn out, under, around and over such securing-coil, and both plies, or at least the outer, free edge portion 4 of the outer-ply (Figs. 2 and 3) firmly secured to their respective adjacent cover-boards A and A', respectively; as clearly shown in Figs. 1, 2 and 3, in any desired manner; usually by cementing the same thereto by any suitable adhesive cementing material, such as glue, etc. Such backwardly extending securing portion 4 may if desired, form the entire inside covering surface of its cover-board, but usually extends only to the point indicated by 5' in Figs. 1, 2 and 3, and a second sheet piece 5 is glued or cemented over such strip 4 and over the entire inside surface of the cover-boards, as shown in Fig. 2.

The binding-cover so formed usually is provided with an outer covering sheet 6 of leather, canvas or other suitable flexible fabric, firmly secured to the cover-boards in any desired manner, (usually by glue or other suitable strongly adhesive material) formed of a single piece, which extends from the top cover-board A around and over the back spring or springs C, C' and C'', as clearly shown in Fig. 2; and a stiffening piece of any desired material 7 may if desired, be placed within such back as indicated in Fig. 2.

The binding key-piece 9 of my improved fabric securing-joint, located within the securing-coil 1 of the securing resilient back-spring or springs C, C', and C'' (Figs. 1, 2, 3 and 5) is preferably of the same shape in

cross-section as is the coil, so as to force the fold of the fabric-strip out into contact with the inner surface of the peripheral wall of the coil at all points, and extends longitudinally substantially the full length of the back of the binder, so as to secure together the plurality of back-springs C, C', and C''; and such securing-key or rod 9, is usually provided at one end, usually adjacent to the slotted head 11, with a male-screw thread 75 formed on a short portion of the rod slightly larger than the main or body portion of such rod, which male-thread coacts with a female-thread formed in the securing-coil 1, to prevent accidental displacement of the rod; and the fabric 3 at the point indicated by the line 13, in Fig. 5, is cut away, so as not to cover and interfere with the screw-joint thus formed.

In some cases where it is not desired to remove such securing-key or rod 9, the same may be secured in place by swaging rivet heads upon either end, so as to permanently secure the same in position.

Fig. 5 shows my fabric securing-joint in top view with the fabric 3 firmly secured thereto, in the form of a straight-edge having the securing-coil 1, which straight-edge may be secured in any desired position by suitable screws 8, and may be thus used in devices other than bookbinders.

In order to insert (or remove) the body to be bound, such as a body of loose leaves, or a pamphlet or book, magazine, telephone directory, etc., in my improved form of binder, it is only necessary to spring the cover-boards back into the position indicated in Fig. 2, with the front edges of the two coverboards A and A' abutting, when the securing back-springs C, C' and C'' will be forced open, and the body of leaves or pamphlet B may be instantaneously removed, and as quickly reinserted; when, upon the release of the front edges of the coverboards of the cover from pressure, the resiliency of the spring or springs C, C' and C'', will be sufficient to firmly force the securing edges 12 of the back-piece firmly against B, with sufficient force to hold the same firmly in position in the binder or back-piece, against any accidental or unintentional displacement.

I do not intend to limit myself in a joint for securing fabrics to metallic or other straight-edges, in which such straight-edge is provided with a narrow slotted securing-coil through which a fold of the fabric is inserted into the coil through the slit, and extends around, back and over the coil, to a structure in which the coil is of substantially cylindrical form in cross-section, as the coil may be made of various shapes in cross-section, and the securing key or rod 9 inserted therein, may also be of many shapes in cross-section; but is usually of the same shape as

is the cross-section of the coil. Neither do I intend to limit myself to any particular material to be used in the construction of the whole or any part of the device or devices 5 herein described, disclosed and claimed; and while I prefer to form the straight-edge of suitable resilient metal, and the securing-rod also of suitable metal, the same may be of any other suitable material; and the securing-key or rod may be of any material of suitable shape in cross-section; and many other changes and modifications in the construction herein mentioned and disclosed, may be made without departing from the 10 scope of my invention.

I claim:—

1. A longitudinal member having a straight edge; a securing-coil of substantially cylindrical form in cross-section 20 formed integral therewith and longitudinally thereof; a flexible-fabric folded upon itself with the fold lying in the securing-coil; and a securing-key-piece or rod located in the fabric-fold within the securing- 25 coil, and extending the entire length of such fold and coil, of the same substantially circular contour as the securing-coil but of such diameter as to fit tightly within the fabric-fold.

30 2. A longitudinal member having a straight edge; a securing-coil of substantially cylindrical form in cross-section formed integral therewith and longitudinally thereof; a flexible-fabric folded upon 35 itself with the fold lying in the securing-coil; and a solid securing-key-piece or rod located in the fabric-fold within the securing-coil and locked in such coil against accidental displacement, which is of substantially 40 the same circular contour as the securing-coil but of such diameter as to fit tightly within the fabric-fold.

45 3. A longitudinal member having a substantially circular cylindrical hollow securing coil formed integral therewith and longitudinally thereof; a flexible-fabric folded upon itself with the fold lying in the securing-coil; and a solid securing-key-piece or rod located in the fabric-fold within the securing-coil and extending through the 50 length thereof.

55 4. A longitudinal member having a straight-edge; a securing-coil formed integral with the longitudinal edge of the straight-edge in such manner that a narrow slit is left between the outer edge of the coil and the abutting inner face or surface of the main body portion of the straight-edge; a flexible-fabric folded upon itself with the 60 fold lying in the securing-coil; while the main body portion of such fabric extends out through the slit; and a rigid securing-key-piece or rod located in the fabric-fold within the securing-coil.

65 5. A longitudinal member having a

straight-edge; a securing-coil of substantially cylindrical form in cross section formed integral with and longitudinally of the straight-edge in such manner that a narrow slit is left between the outer edge of the 70 coil and the abutting inner face or surface of the main body portion of the straight-edge; a flexible-fabric folded upon itself with the fold lying in the securing-coil, while the two plies of the main body portion 75 of such fabric extend out through the slit, and one or both plies are permanently drawn around and over the securing-coil; and a securing-key-piece in the form of a rigid-rod located within the fabric-fold in the se- 80 curing-coil.

85 6. A longitudinal member having a straight-edge; a securing-coil formed integral with and longitudinally of the straight-edge in such manner that a narrow slit is left 85 between the outer edge of the coil and the abutting inner face or surface of the main body-portion of the straight-edge; a flexible fabric having its outer free end folded upon itself, with the fold lying in the securing-coil, with the main body portion extending out through the slit, and being drawn back tightly over the periphery of the coil; and a securing key-piece or rod lying within the fabric-fold and securing-coil, and extending 90 the length thereof.

95 7. A back-piece securing-spring for binders, formed of resilient spring metal, bent into substantially segmental form and provided at each of the securing-edges with an 100 integrally formed substantially cylindrical hollow securing-coil, between the outer edge of each of which coils, and the abutting face or surface of the main or body portion of the segmental back-piece is left a narrow 105 slit; a piece of folded fabric with the fold entering such securing-coil through said slit; and a locking member within said fold to secure it within the coil.

110 8. A back-piece securing-spring for binders, formed of resilient spring metal, bent into substantially segmental form, and provided at each of the securing-edges with an integral substantially cylindrical hollow securing-coil, formed by turning the metal 115 inward so as to leave a slit between the outer edge of such coil, and the abutting inner face or surface of the main or abutting portion of the segmental back-piece; a piece of folded fabric, (one for each coil), entering 120 each of said securing-coils through their respective slits; and a locking-member within each of said folds to secure the same within the coil; the construction being such that when the outer free end of the fabric so 125 locked in the coil is drawn outward over the periphery of the coil, it will have frictional contact therewith.

130 9. In a binder, a back-piece having forwardly projecting securing binding-edges,

- each in the form of a coil having a slit between its edge and the abutting face or surface of the main body portion of the back-piece, each of which coils is integrally formed at a longitudinal edge of such back-piece; cover-boards; a securing-strip of flexible-fabric for each of the securing-coils having a fold thereof lying in its coil with the two plies thereof extending out through the slit; a securing-key-piece or rod located within each fabric-fold and securing-coil and extending the width of the binder; and means for securing the fabric-securing-strips to their respective cover-boards.
10. In a binder, a back-piece having forwardly projecting securing binding-edges, each in the form of a coil having a slit between its edge and the abutting face or surface of the main body portion of the back-piece, each of which coils is integrally formed at a longitudinal edge of back-piece; a securing-strip of flexible-fabric for each of the securing-coils having a fold thereof lying in its coil with the two plies thereof extending out through the slit; a securing-key-piece rod located within each fabric-fold and its securing-coil and extending the width of the binder; a front and a back cover-board; means for securing one of the fabric-securing strips to the front and the other to the back cover-board; and an outer covering-sheet of flexible fabric or material secured to the front and back cover-boards and exteriorly covering the back-piece.
11. In a binder; a plurality of securing back-pieces each having securing edges facing one another, which edges are each in the form of a coil formed integral with the back-piece in such manner as to leave a narrow slit between the edge of the coil and the adjacent abutting face or surface of the main body portion of the back-piece, which back-pieces are arranged end to end with their securing-coils in alignment; cover-boards; a securing-strip of flexible-fabric for each of the cover-boards secured thereto, and having a fold thereof lying in the securing-coils on that side of the several back-pieces, with the two plies thereof extending out through the slit; and a securing-key-piece or rod lying within the fabric-fold within the securing coils on each side of all the back pieces.
12. In a binder, a plurality of back-pieces in the form of segments bent up from spring-resilient-metal, each having securing edges facing one another, which edges are each in the form of a coil formed integral with the back-piece in such manner as to leave a narrow slit between the edge of the coil and the adjacent abutting surface or face of the main body portion of such back-piece, which back-pieces are arranged end to end with their securing-coils in alignment; cover-boards; a securing-strip of flexible fabric for each of the cover-boards secured thereto, and having a fold thereof lying in the securing-coils on one side of the several back-pieces, with the two plies thereof extending out through the slit and being drawn around and over the periphery of the securing-coil whether the binder be in the closed or open position; and a rigid securing-key-piece or rod lying within each of the fabric-folds within the securing-coils on each side of all the several back-pieces.
13. In a binder, a plurality of back-pieces in the form of segments bent up from spring-resilient-metal, each having securing edges facing one another, which edges are each in the form of a coil formed integral with the back-piece in such manner as to leave a narrow slit between the edge of the coil and the adjacent abutting surface or face of the main body portion of such back-piece, which back-pieces are arranged end to end with their securing-coils in alignment; cover-boards; a securing-strip of flexible-fabric for each of the cover-boards secured thereto, and having a fold thereof lying in the securing-coils on one side of the several back-pieces, with the two plies thereof extending out through the slit; and a securing-key-piece in the form of a rigid rod extending through each fabric-fold and its line of securing-coils, and being secured in place against accidental displacement by a screw-joint between such rod and the securing coil.
- Signed at the borough of Manhattan, city, county and State of New York, this eighteenth day of September, 1913.
